UNITED STATES PATENT OFFICE

2,178,911

SPLIT-FOOT KNITTING MACHINE

Robert H. Lawson, Pawtucket, R. I., assignor to
Hemphill Company, Central Falls, R. I., a corporation of Massachusetts

Application August 16, 1935, Serial No. 36,563
Renewed April 28, 1939

25 Claims. (Cl. 66—43)

This invention relates to split-foot knitting machines and more particularly to circular knitting machines adapted to knit ladies' hosiery or half hose in which either the high-splice and instep, the sole and instep or both, are adapted to be knit in a reciprocatory manner to produce the well-known split-foot stocking.

This case is a continuation as to all common subject matter of the applicant's co-pending case, United States Serial Number 439,976, filed March 29, 1930, now Patent No. 2,083,027.

In the drawings:

Fig. 1 shows in elevation a full length, fashioned stocking produced upon the machine herein described;

Figs. 2 through 5 show modifications of the foot structure of a stocking similar to that shown in Fig. 1, which are capable of being produced on the same machine herein described;

Fig. 6 is a front elevation of the split-foot knitting machine embodying my invention;

Fig. 7 is an elevation showing in general the mechanism as viewed from the right side of Fig. 6;

Fig. 8 is an elevation taken from the opposite side of Fig. 6;

Fig. 9 is a plan view, partly in section, showing the jack cams and their operating mechanism;

Fig. 10 is a plan view, partly in section, showing the main cam block, narrowing picks and instep cams;

Fig. 11 shows in elevation the mechanism of Fig. 10;

Fig. 12 is a plan view showing in detail one of the high-splice and narrow sole cams and part of its operating mechanism;

Fig. 13 is an elevation of the mechanism shown in Fig. 12;

Fig. 14 is a plan view similar to Fig. 12, but showing the other high-splice and double sole cam;

Fig. 15 is an elevation of the mechanism shown in Fig. 14;

Fig. 16 is an elevation showing the instep cams and some of their operating mechanism;

Fig. 17 corresponds to Fig. 16 but shows the cams in reverse position;

Fig. 18 is a view of the instep cams as seen from the center of the needle cylinder;

Fig. 19 is a detail view showing operating mechanism for the eyelet closing cam, auxiliary cam block and auxiliary center cam;

Fig. 20 is a view showing in detail some of the mechanism for operating the high-splice and narrow sole cams;

Fig. 21 is a detail view of part of the mechanism showing in Fig. 20, the cam operated lever shown in opposite position;

Fig. 22 is a development showing a portion of the needle cylinder, long butt needles and short butt needles in section; 5

Fig. 23 is a development showing in section the corresponding portions of the needle cylinder and jacks therein;

Fig. 24 is a sectional view of the needle cylinder showing the lower part of a needle and its jack in operating position; 10

Fig. 25 is an elevational view showing the operating mechanism for the widening picks;

Fig. 26 is a diagrammatic view showing the auxiliary knitting cams, parts of the needle raise cams and an auxiliary needle raise cam; 15

Fig. 27 is a sectional view showing the needle about to draw a stitch over the novel sinker;

Fig. 28 is a sectional view corresponding to Fig. 27 and showing the stitch completely measured; 20

Fig. 29 is a sectional view similar to Figs. 27 and 28, and showing the novel sinker acting to relieve the fabric of strain;

Fig. 30 is a sectional view showing a needle in raised position; 25

Fig. 31 is a plan view showing the sinker cap and certain of the sinker cams;

Fig. 32 is similar to 26 but shows a modification of the mechanism therein shown; 30

Fig. 33 is a detail of one type of sinker cam;

Fig. 34 shows in detail another type of sinker cam;

Fig. 35 is a sectional view showing the sinker head and mechanism for operating the sinkers in the auxiliary side during heel and toe knitting; 35

Fig. 36 is a diagrammatic view showing the path of needles and jack butts through the cams during knitting of the leg;

Fig. 37 is a diagrammatic view showing the knitting of the high-splice, the needles moving in a clockwise direction; 40

Fig. 38 is similar to Fig. 37 but shows the operation in an anti-clockwise direction;

Figs. 39 and 40 are diagrammatic views showing reciprocations in both directions during heel and toe knitting; 45

Fig. 41 is a diagrammatic view showing knitting during the instep and sole of the stocking;

Fig. 42 is a diagrammatic view showing knitting of the instep and sole adjacent the ring toe at the so-called bunion patch; 50

Fig. 43 is a diagrammatic view showing knitting of the ring toe; and

Fig. 44 is a diagrammatic view showing operation of needles and jacks prior to formation of a small heel.

As in the co-pending case Ser. No. 439,976, above mentioned, the machine herein disclosed is preferably, although not necessarily, of the rotary needle cylinder, latch needle type. The machine is capable of knitting a split-foot stocking of exceptional quality since the leg and instep are both knitted at the auxiliary feed and the welt, high-splice, sole, ring toe, and the heel and toe are knitted at the main feed or side of the machine. While the idea of knitting the leg and instep at the same feed (auxiliary feed) is not in itself new, machines constructed for knitting such a split-foot stocking have not been particularly satisfactory especially in regard to simplicity and automatic control of the various knitting cams during knitting of the several parts of the stocking.

The machine herein disclosed is adapted to produce a suture of the type shown in the patent to Augustin Gagne No. 1,673,764, although any conventional suture may be employed without departing from the spirit of the invention.

It is general practice when knitting split-foot hosiery to knit the high-splice and/or sole upon approximately one-half the series of needles, generally short butt needles, and the instep on the remaining portion of the needles, generally long butt needles. The series of needles which I employ is preferably divided into an equal number of long and short butt needles as above mentioned, but in addition I employ a number of jacks at either side of the needle cylinder, said jacks being placed directly beneath the short butt needles which adjoin the long butt needles, and further, these jacks may be divided into any convenient number of long and short butts. By automatic and selective operation of these long and short butt jacks I am able to so control any desired number of short butt needles which are adjacent the long butt needles that the instep may be produced on more than one-half the series of needles and at the same time, the high-splice and/or sole will be produced upon less than one-half the complement of needles, such practice being desirable when knitting ladies' hosiery for wear with slippers or sandals. By properly dividing the said jacks into long and short butts, I am able to produce the heel upon a relatively small number of needles so that the point of intersection of the narrowed and widened portions of the same will be separated a few wales from the suture seam itself, this small heel being possible of manufacture in combination with the narrow high-splice and sole or in combination with either one as desired.

During knitting some of the needles draw stitches at one set of cams and as the rotation or oscillation of the needle cylinder continues, these same needles will again pass under the opposite set of knitting cams and again tend to draw or stretch the loops which are held in the throats of sinkers, said sinkers being pushed inwardly to their full extent. The mechanism herein shown very effectively prevents the production of defective fabric from the above mentioned causes and I have disclosed a new type of sinker and a modified form of needle raise cam which is adapted to actuate the needles to relieve the strain on the loops when the needles pass through the auxiliary knitting cams.

Referring to Figs. 1 through 5 which show various modifications of split-foot stockings which I may produce, these stockings preferably al-

though not necessarily, are made by knitting from top to toe and a welt may be knitted upon the machine prior to knitting the remainder of the stocking or, if desired, a welt may be knitted in another machine and transferred to the split-foot machine prior to knitting the stocking itself.

In Fig. 1 is shown a stocking comprising the welt 1 and a fashioned leg portion 2 which extends down to the top of the high-splice 3. The welt is preferably knitted at the main feed and a leg portion is knitted at an auxiliary feed, both being produced by round and round knitting. When the beginning of the high-splice portion is reached reciprocatory or split-foot knitting is commenced, the high-splice 3 being knitted at the main feed and the instep portion 4 being knitted at the so-called auxiliary feed. Following this practice the leg and the instep will be knitted from the same yarn and by the same set of cams so that no contrast will appear at the dividing line between the leg and instep. An extra reinforcing yarn may be knitted into the high-splice for any desired width as shown at 5. The high-splice may be made on one-half the needles or may be knitted on less than that number of needles depending upon the set-up of jacks used under the short butt needles. In the stocking shown, the high-splice is knitted on a few less than one-half the complement of needles and the sole 6 is also produced by knitting upon a few less than one-half the short butt needles. The heel 7, narrowed and widened in the usual manner, is knitted upon a few needles less than the high-splice and sole were produced upon so that the corner or intersection of the narrowing and widening segments thereof will be spaced a few wales from the suture. Such a construction results in an exceptionally strong and wear resistant foot. Several courses before the ring toe 8 is reached, the jacks are taken out of action and both instep and sole are knitted upon an equal number of needles to produce the so-called bunion patch 9. After the ring toe 8 has been knitted in a conventional fashion, a narrowed and widened toe 10 may be knitted in any desired way. The modification at Fig. 2 is produced in a manner similar to that previously disclosed relative to Fig. 1, however, the high-splice 11 is knitted upon fewer needles while the heel 12 and sole 13 are knitted upon one-half the full complement of needles.

In Fig. 3 I have shown a modified form of foot in which the high-splice 14 and sole 15 are knitted upon one-half the needles and the heel 16 is knitted upon a few less than one-half the needles.

In the modification shown in Fig. 4 the high-splice 17 and heel 18 are knitted as in Fig. 3, the sole 19 being dropped down several wales and knitted upon comparatively few of the short butt needles. Such a construction results in a strong, wear resistant heel in combination with a cradle foot, such stocking being popular for wear with sandals.

In Fig. 5 the high-splice and sole have been knitted on less than half the needles while the heel 21 has been knitted upon fewer needles than sole 22 has. No reinforcing has been done in the high-splice. These modifications are merely given as examples of the many combinations of foot structure which I may automatically knit upon the machine herein disclosed, the only change necessary to convert from one foot to another being that in replacing one combination of jacks by another.

Referring to Figs. 6, 7 and 8 which show the

general construction of this split-foot machine, a frame 23 has mounted thereon the so-called circular base 24, main drive shaft 25 and pulleys 26, 27 and 28 employed as high speed, slow speed 5 and idling pulleys respectively. A needle cylinder 29, herein shown as of the rotary type, carries in the usual slots or tricks, latch needles which are adapted to draw stitches over sinkers mounted in a sinker head 30. A latch ring 31 10 of more or less conventional construction has pivoted at 32 yarn guides 33 which are controlled in the manner usually employed in the "Banner" type machine, by levers 34 pivoted in an enclosure 35 and which are in turn actuated through 15 the connection of wires (not shown) which extend down to a corresponding series of levers 36 one end of which bears upon suitable cams generally designated at 37 upon cam drum 38 rotating with the usual cam shaft 39. Another 20 cam 40 shown at the right of drum 38 is effective through a lever 41 to shift a clutch at properly timed intervals for changing from rotary to reciprocatory knitting and vice versa. Such mechanism is well known in "Banner" machines 25 and is illustrated sufficiently in the Gagne patent herein mentioned, so that no further disclosure of the same need be given at this time.

A main cam block is generally designated at 42 and is mounted upon cam plate 43 which is 30 in turn capable of being raised and lowered for a slight extent by the usual fashioning cams (not shown) on a drum herein generally indicated at 44 and mounted upon main cam shaft 39.

A second cam block, herein termed the auxiliary cam block, is generally designated by numeral 45. This auxiliary cam block is mounted upon the other half 46 of cam plate 43 and this cam plate is also adjustable for purposes of fashioning or changing stitch length by means of a 40 bar sliding in bracket 47, said bar carrying a stud 48 at its lower end which stud is in contact with one arm 49 of a bell crank lever 50. The other arm 51 of bell crank lever 50 extends downwardly and carries at its lower end a series of 45 contact elements 52 which are separately adjustable by means of screws 53. These contact members 52 bear against certain cams, one of which is designated by numeral 54 upon a drum 55 rotating on shaft 56. These cams are adapted 50 to control the stitch length at the auxiliary feed by raising or lowering cam block 45 at the proper time.

Bracket 47 extends to the left as is shown in Fig. 8, forming an arm 57 which serves to hold 55 a pin 58 about which lever 50 swings. At an intermediate portion of bracket 47 is bolted or otherwise secured an extension 59 which in turn is secured to the upper end of an A-bracket 60. This bracket 60 is firmly secured to the base of 60 the machine by bolts 61 passing through the feet 62. This bracket serves very rigidly to hold bracket 47 and its attached mechanism in fixed position and further, serves to guide the lower end of lever arm 51. As seen in Figs. 6 and 8, bracket 60 has an extension 63 which terminates in an angular portion 64 in alignment with another projection shown at 65. Screws 66 and 67 are adjustably threaded into these extended portions of bracket 60 and serve to guide the 65 lower end of 51 so that it will swing in a predetermined plane, thus avoiding vibration and assuring that contact members 32 will bear against their cams in a proper manner.

The shaft 56 carrying cam drum 55 is mounted 70 for rotation with a bearing 68 at the upper

end of a bracket 69 bolted to an angular brace 70 which is in turn rigidly connected to a frame of the machine. This shaft 56 extends across the machine at the rear side thereof and carries a sprocket wheel 71 at the opposite end as shown in Fig. 7. This sprocket wheel 71 is driven by a suitable chain 72 which engages another similar sprocket wheel (not shown) fast to cam shaft 39. A chain guard 73 is attached to the frame and serves to protect the enclosed mechanism from dust and dirt and at the same time prevents the operator from getting caught in the chain or in the sprocket. An arm 74 pivoted at 75 carries at its opposite end a weighted tensioning sprocket 76, thus maintaining the 15 chain under suitable driving tension at all times.

In the same Fig. 7 are shown the belt shifter generally indicated at 77, the depending lug 78 for engaging suitable cam projections upon drum 79, all for the purpose of shifting the belt from high speed to low speed or loose pulleys as the case may be, such mechanism being the conventional construction on "Banner" and like machines. The high-splice and toe of the stocking may be reinforced by an additional yarn inserted throughout any desirable portion of the width of the same. Referring to Figs. 7 and 9, there is described mechanism which is used for introducing this reinforcing yarn which is knitted at the main yarn feed. As mentioned before, a series of yarn guides 33 are pivoted at 32 in the latch ring or carrier ring 31 and these yarn guides are normally controlled either to feed their yarns to the needles or to withdraw the yarns out of feeding relation to the 35 needles in accordance with certain cams 37 which contact levers 36 connected through wires (not shown) to other levers 34 which engage the yarn guides and actuate them in a normal manner. To one of these levers 34 which contacts with the particular yarn guide which is to feed the extra reinforcing yarn, I connect a vertically extending link 80, Fig. 9, to a lever 81 pivoted at 82 on a fixed bracket 83. The bracket 83 extends in an angular fashion at either 40 side to form a connecting base 84 which attaches through suitable bolts to the circular base of the machine. At the opposite end lever 81 is slotted and engaged by a laterally projecting pin 85, said pin being connected to the outer 45 end of a lever 86 which is fast to shaft 87. Shaft 87 is capable of being rocked through a small angle by mechanism presently to be described, that is, when the reinforcing finger is to be operated by it, but at other times the said shaft 50 is shiftable along its axis to a position which renders it inoperative. The shaft 87 is rotatable and also capable of being shifted axially in bearings 88, 89 which extend upwardly from a bracket 90 carried by the circular base. At its outer 55 end, shaft 87 has fixed thereto a lever 91 which carries at its lower end a hardened cam follower 92, Fig. 7. A cam plate 93 is fixed to the end of "104" gear shaft 94 and carries thereon cam segments 95, 96, 97 and 98 and these segments 60 are adjustable about the circumference of cam plate 93 and form certain spaces or depressions 99 and 100 approximately 180 degrees apart. By adjusting cam segments 95-98 it is possible to vary the angular extent of these depressions and thus, the time intervals the reinforcing yarn finger will remain in feeding position, it being understood that when follower 92 rides upon the concentric surface of the cam segments the reinforcing yarn is out of feeding relation to the 65 70

needles but when said follower drops into one of these depressions, the extra reinforcing yarn is fed to the needles knitting the high-splice or toe as the case may be. For the purpose of quickly actuating follower 92, lever 91 and the attendant mechanism as the follower drops within one of the depressions, I provide a suitable tension spring 101 connected at one end to lever 91 and at the opposite end of a pin 102 projecting from a suitable part of the circular base.

At the end of shaft 87 opposite that to which lever 91 is connected, I make fast a collar 103 which has a suitable groove 104 therein. On a bracket 105 attached to some suitable part of the machine frame I pivot at 106 a bell crank lever having a horizontal arm 107 and a vertical arm 108, said vertical arm carrying a projecting pin 109 for engaging within the slot 104. At the other end of horizontal arm 107 I pivot at 110, the upper end of a depending link 111 which connects at its lower end to a lever 112 which bears upon a cam (not shown) on the cam drum 112', which is suitably proportioned to shift shaft 87 axially in its bearings 88 and 89. In Fig. 9 shaft 87 is shown in its inoperative position, said shaft being pushed to the right as seen in the figure until follower 92 is out of operating position relative to the cam segments 95-98. The shaft 87 is pushed to the right against the action of a compression spring 113 bearing at one end against bearing lug 88 and at the other against a collar 114 clamped to shaft 87. When lever arm 112 falls off its supporting cam (not shown) spring 113 will function to shift shaft 87 to the left until stopped by collar 115 striking bearing lug 89. In this position follower 92 will engage cam segments 95-98 in which case the reinforcing finger will be operated. Pin 85 has been made of sufficient length to slide within the co-acting slot in lever 81 so that it will always engage the same in either of its positions.

The mechanism just described controls the splicing or reinforcing yarn finger only at such times as splicing is going on. That yarn finger is under the usual control from the main pattern drum and will be allowed to move to operative position at the beginning of splicing and will be withdrawn at the end of splicing in the usual way. That control from the main drum is not illustrated in this case since the same is well-known by those skilled in the art and is illustrated and described in Lawson Patent #2,083,027 at Figs. 19 and 20 and the description relative thereto.

The main cam block generally designated by numeral 42 is shown in Figs. 6, 10, and 11; the cams being diagrammatically shown in Figs. 36 through 44. This cam block is capable of being retracted when needles are to be leveled for purposes of transfer and at other desired times by means of bell crank lever 116 connected to the block itself by a link 117, said bell crank lever being actuated by a rod 118 which operates from a cam drum in a conventional manner. A spring 119 and plunger 120 operate to hold the cam block 45 inwardly against the cylinder except when it is to be retracted as above mentioned.

This cam block carries knitting cams 121, 122, upper center cam 123 and lower center cam 124. Knitting cam 121 is capable of being retracted during round and round knitting by means of a link 125 connected to a stud 126 fast in the end of a sliding stem which forms an extension of the cam 121. Link 125 is connected to one arm of a bell crank lever 127 and the other end 50 of that lever is connected to a depending link 128

the lower end of which is pivoted to one arm of lever 129 pivoted at 130. The other arm of this lever 129 is connected to an operating rod 131 which is actuated by an appropriate cam on main cam shaft 39. A spring 132 is connected at one end of rod 131 and at its other end to the machine frame and is under a suitable tension to keep knitting cam 121 inwardly against the cylinder except when drawn outward under the influence of the cam above mentioned. Narrowing picks 133 and 134 are also carried by this main cam block and narrowing pick 133 is automatically swung out of the way when knitting cam 121 is withdrawn from action by means of a finger 135 which slides with the cam and swings pick 133 15 by means of a pin 136 projecting therefrom.

A bracket 137, shown in detail in Figs. 10, 11, 16, 17 and 18, constitutes a suitable mounting for upper instep cam 138 and lower instep cam 139. This bracket 137 is securely bolted to cam plate 20 43 and has two slots 140 and 141 in which stems 142 and 143 of the upper and lower instep cams slide. A plate 144 is secured to bracket 137 by screws 145 and serves to hold cam stems 142, 143 within their operating slots. It is a feature of 25 these so-called instep cams and their operating mechanism that either cam may be actuated independently of the other or that both cams may be operated at the same time. Lower instep cam 139 is normally held in position to engage long 30 butt needles by means of a spring 146 which encircles a plunger 147 attached to said cam and also bears within a drilled hole 148 within the bracket. The stem 143 has a slot shown at 149, said slot being beveled at its rear end as shown 35 at 150. An operating rod 151 slides within a vertical opening passing upwardly through bracket 137 at the left hand edge of slots 140, 141, this rod being cut away as shown at 152 to allow a limited movement of cam 139 and its stem 143; 40 and further, a beveled surface 152' on the operating rod acts to withdraw cam 139 from operative position as the said rod is drawn downwardly whereby beveled edges 152' and 150 co-act to cam said stem 143 outwardly.

The upper instep cam 138 has a short stem 142 45 which slides within groove 140. Operating rod 151 is cut away to leave only a narrow portion 153 extending upwardly. Bracket 137 is slotted at 154 and a pin 155 fast to stem 142 projects upwardly through this slot. At 156 I have pivoted 50 a bell crank lever 157, one arm of which has a slot 158 engaging said pin and the other arm carrying, connected thereto at 159, a link 160 which is actuated by suitable mechanism to rock 55 bell crank lever 157 and move the cam 138 into and out of position. The other end of link 160 has adjustably attached thereto a connecting element 161 which is pivoted at 162 to one arm 163 of another bell crank lever. This bell crank lever 60 is pivoted at 164 to a bracket 165 fast to the yarn lever bracket of the machine and the other arm 166 of said lever has a connection 167 through a hole in which rod 168 projects. This rod 168 is connected to one end of a lever the other end 65 169 of which contacts the pattern chain 168' shown in Fig. 6. Two collars 170 and 170' are clamped to the rod 168 and maintain springs 171 and 172 under tension so that loose collars 173, 174 will act upon lever arm 166 through connection 70 167 in a resilient manner.

As before described, rod 151 operates to withdraw the lower cam 139 from operative position. For the purpose of actuating this rod 151 I have pivoted a bell crank lever having arms 175 and 75

176 about a pin 177 in a lug 178 extending downwardly from a plate 43. The arm 175 is slotted as shown at 179 and a pin 180 works in said slot and is attached by threaded engagement, to the lower end of rod 151. At the outer end of arm 176 is connected a link 181 which swings about pivot point 182. Link 181 extends over to the right, through the frame of the machine and connects to the upper end of clutch shifter 41 so that the lower instep cam is actuated upon going into and out of reciprocatory knitting.

The auxiliary cam block has been generally designated by numeral 45 and carries knitting cams 183 and 184, center cam 185, guard cam 186 and auxiliary raise cam 187, this latter cam being preferably formed in two parts having an overlapping joint at the center, see Fig. 32. These cams function at the auxiliary side of the machine to knit the leg portion during circular knitting and the instep portion of the stocking by reciprocatory or split-foot knitting. The mechanism for raising and lowering the block for purposes of fashioning or changing stitch length through its connection to plate 46 has been previously described.

Widening picks are also carried on this auxiliary cam block and are designated in Figs. 6 and 25 by numerals 188 and 189. The mechanism for operating these picks is of simplified and novel construction. On a yoke 190 attached to the auxiliary cam plate, pivoted at opposite points 191 and 192 are arms 193 and 194 adapted to swing in opposite directions under the influence of a plunger 195 which extends downwardly through said yoke and is operated in a known manner by a widening pick lever 196. Plunger 195 carries a laterally extending pin 197 which engages corresponding slots 198 in the ends of levers 193, 194. Widening pick lever 196 is actuated to push plunger 195 upwardly which swings the arms 193, 194 in one direction and a spring 199 attached at one end to the yoke and at its other end to pin 197 is under sufficient tension to draw plunger 195 in the downward direction. Widening picks 45 188, 189 carry pins 200, 201 extending in a rearward direction. These pins are engaged by hardened contact elements 202, 203 which are adjustably fixed at the outer ends of the oppositely swinging arms, said adjustment being possible by sliding screws 204 in slots 205 before tightening the same to clamp the respective hardened elements 202, 203 to their arms.

In Figs. 22, 23 and 24 I have shown the needles and jacks which it is necessary to employ for making such a stocking as is illustrated in Fig. 1, for example. Certain sections of the needle cylinder 29 have been represented as if developed into a plane in Fig. 22. Short butt needles 206 and long butt needles 207 have been shown therein, it being understood that the machine contains substantially an equal number of each type of needle, separately divided at the opposite halves of the cylinder.

In Fig. 23 I have shown the corresponding portions of the needle cylinder and certain long butt jacks 208 and short butt jacks 209 disposed therein. For making such a stocking as is shown in Fig. 1, I place at either side of the needle cylinder under the terminal short butt needles, nine long butt jacks and adjacent these long butt jacks, three short butt jacks. I have chosen this division of jack butts merely for purposes of illustration and it is to be fully understood that the invention is in no way dependent upon the relative number of long and short butt jacks em-

ployed, but that any convenient number of such jacks may be used depending upon how much the suture line is to be dropped below the center of the stocking and how far removed from that suture line the heel is to be commenced and ended.

The function of these jacks will be fully explained later when a full disclosure of machine operation for making such a stocking as shown in Fig. 1, is given.

I will now describe the cams necessary for actuation of the jacks mentioned above and will refer to Figs. 8, 9, 12-15, 20 and 21. In Fig. 9 are shown the six cams which function upon said jacks, said cams being designated by numerals 210, 211, 212, 213, 214, and 215. The cams designated at 211 and 215 are of triangular shape and are rigidly connected to the circular base by means of screws passing through the extensions 216 and 217. Cam 210 is known as the suture cam and is permanently attached to a stem 218 which slides in a suitable bracket 219 which is adjustably connected to the circular base. A sliding member 220 which carries a stepped and inclined slot 221 is adapted to be reciprocated within said bracket by mechanism later to be described. Cam stem 218 has secured therein a pin 222 which projects through the slot 221 and thus, when element 220 is reciprocated, the pin will be forced in a radial direction within stepped slot 221 so that said cam will be positioned either in its inactive position as shown in Fig. 9, an intermediate position wherein it will engage only long butt jacks, and in a third or inner position where it will engage both types of jacks. Attached to a pivot point 223 on one end of the base of bracket 84 is a bell crank lever having one arm 224 connected to slide 220 and another arm 225 to which is attached a link 226. This link 226 is actuated by bell crank lever 227 pivoted upon a bracket 40 228 fixed in an upright position on the circular base. Depending from the horizontal arm of the last mentioned lever is a link 229 shown clearly in Fig. 7, said link having an adjustable connection 230 at its lower end which pivots at one end of a lever 231 itself pivoted at 232 on an angular bracket 233. This lever 231 extends to the other side of its pivot point and terminates in a cam engaging toe 234. This toe is contacted by appropriate cams on the stop motion cam drum 50 79 which through the linkage just described, actuates slide 220 and thus cam 210. A spring 235 attached to the side itself and another spring 236 connected to lever 231 function to return said linkage and cam to their initial position after 55 toe 234 has passed over the cams before mentioned.

Cams designated at 212 and 214 and known as the high-splice and double sole cams, are actuated by mechanisms shown in Figs. 6, 8, 9, 12-15, 20 and 21. Referring to Figs. 14 and 15 cam 212 has a stem 237 which slides in a bracket 238 connected by suitable screws to the base member 24. A pin 239 extends upwardly from the cam stem and projects through a slot 240 which extends in a radial direction in cap 241 on bracket 238. This pin is also engaged by a slot 242 extending lengthwise of a lever 243 pivoted on the bracket at 244. The last mentioned lever has connected to its free end a link 245 which 70 is adapted to swing said lever about its pivot when a shaft 246 (Figs. 8 and 9) carrying an arm 247 fixed at one end of said shaft and having its other end pivoted at 248 to said link is oscillated. This shaft 246 is mounted for rotation 75

within bearings 249 and 250 which extend from a bracket rigidly attached to circular base 24. Said shaft 246 is rocked at the proper time during the knitting cycle by means of mechanism later to be described. A spring 251 is attached to cam stem 237 and also to the cap 241, said spring being under suitable tension for the purpose of holding cam 212 inward against the cylinder except when held in an outer position by mechanism herein described.

Cam 214 has a stem 252 which extends in a radial direction and is adapted to slide in a bracket designated by numeral 253. A lever 254 is pivoted at one end to bracket 253 as shown at 255, the other end of said lever being connected at 256 to a link 257 which connects to an arm 258 fast to shaft 246. Lever 254 has a slot 259 therein which engages a pin 260 extending upwardly from cam stem 252. Thus it can be seen that when shaft 246 is rocked, cam 214 will be drawn away from the needle cylinder or will be allowed to bear inwardly against the same. Cam stem 252 has attached to its outer end a block 261 to which is also connected an angular arm 262 which acts under the influence of a spring 263 attached to said arm and to bracket 253, resiliently to press cam 214 inwardly. At certain times cams 212, 214 are maintained inwardly against the cylinder and again in an extreme outer position where they do not contact either long or short butts and at other times in an intermediate position where they will engage long butt jacks only. In the intermediate position I have provided a novel mechanism which operates to assure that said cams will be maintained exactly the right distance from the needle cylinder. Such mechanism makes it possible to operate the machine satisfactorily with no danger of operating any other jacks than those desired, this being possible even though the operating mechanism itself is imperfectly adjusted and also has loose fitting connections therein. About the periphery of circular base 24, I provide a sliding cam structure composed of segments 264 and 265 attached to a central U shaped member 266. These segments slide about the circular base on screws 267 passing through slots 268. The segment 265 has attached thereto an angular piece designated by numeral 269 which is adapted, when the segment is in the position shown in Figs. 12 and 13, to extend between bracket 253 and a screw 270 which passes through block 261 connected to the end of the stem of cam 214. Screw 270 may be adjusted within said block to such a position that cam 214 will be spaced from the needle cylinder just a sufficient distance so that it will contact long butt jacks but will miss short butt jacks, that is, when the projecting end of element 269 is inserted beneath the limiting screw 270. In operation cam 214 is controlled in such a way as to allow it to be drawn inwardly by its spring 263 to an extent which would not allow the short butt needles to miss the same, but due to the fact that element 269 is in position, said cam does not go in to its full extent but is held at precisely the proper distance from the needle cylinder to engage the long butts and miss the short butts.

Cam 212 is operated in a similar manner and is held in intermediate position by means of a cam 271 attached to segment 264, said cam bearing upon the head of an adjustable screw 272. This last mentioned screw is threaded within an angular extension 273 attached to the end of stem 237. When said screw is in proper adjustment a lock-nut 274 is tightened against exten-

sion 273 to maintain proper adjustment. A spring 275 is attached at one end to the U shaped member 266 and at the other end to a pin 276 extending outwardly from bracket 238. This spring is under sufficient tension to maintain segments 264, 265 in an inoperative position except when acted upon by one arm 277 of a bell crank lever pivoted at 278 to a bracket 279; said arm 277 bears against a pin 280 threaded into one end of segment 264. The other arm of this bell crank lever has attached thereto at 281 a depending link 282 which is adjustably connected at its other end to an arm 283 which is pivoted at one end on a fixed part of the machine and has a toe at its other end bearing upon a cam drum 284, shown in Fig. 6.

Cam 213 is known as the eyelet closing cam and is attached to one end of a lever 285 pivoted on bracket 253 at a point designated by numeral 286. Lever 285 has a transverse slot 287 therein which encompasses a screw 288 for the purpose of limiting the movement of said lever in both directions. The opposite end of lever 285 has connected thereto at 289 a link 290 which, better shown in Fig. 19, is actuated by a bell crank lever 291 pivoted on a bracket 292. Bell crank lever 291 is actuated by a link 293 which extends downwardly and connects to a cam engaging lever (not shown), said cam engaging lever bearing against a suitable cam on one of the usual cam drums available on the machine.

Referring to Figs. 8, 9, 20 and 21 I will describe the mechanism for actuating shaft 246. There are two levers attached to shaft 246 adjacent one another at the extending end thereof. The longer lever designated by numeral 294 is connected by link 295 to a short lever 296 fast to shaft 297. Shaft 297 has collars 298 clamped thereto by which it is positioned axially relative to a bearing 299 in bracket 300 within which said shaft rotates. At the opposite end shaft 297 has fixed thereto a horizontally extending arm 301 which is actuated by means of link 302 connected at 303 to a cam engaging arm 304. This arm 304 has a toe 305 which bears against suitable cams on cam drum 112' rotating on shaft 56 before mentioned. The cam on drum 112' is shown as having a high portion 305' which is adapted to actuate shaft 246 so that the high-splice and double sole cams will be pushed inwardly against the cylinder and also a low portion 306' by means of which those same cams are pushed inwardly only far enough to contact the long butt jacks but not the short butt jacks.

Shaft 246 may also be rocked on its bearings by means of mechanism which acts to swing the other lever 307 fixed to the end of that shaft. Lever 307 has pivoted thereto at 308 link 309 the other end of which attaches at 310 to one end of a bell crank lever 311. This bell crank lever is pivoted at 312 to a lug 313 on bracket 314 and is resiliently urged in a clockwise direction (Fig. 9) by a spring 315 attached to one end of said bell crank lever and at the other end to a fixed part of the machine. Under the action of this spring, shaft 246 would tend to maintain cams 212 and 214 in full retracted position.

As shown in Figs. 8, 20 and 21, a cam disc 316 is secured to the extending end of "104" gear shaft 94. This cam disc is circular in shape and has connected thereto a pair of cam segments 317 and 318. Cam segment 317 is attached to the disc so that its outer surface is located a short distance inward radially from the periphery of said disc while segment 318 has its

outer surface concentric and flush with the surface of that disc. Bracket 314 extends downwardly in two depending lugs 319 and 320 which are drilled out at their lower ends for reception 5 of a pin 321 which is capable of oscillating and sliding within said lugs. Fixed to pin 321 is a two armed lever 322 which has an upper arm 323 which contacts one end of bell crank lever 311 while the opposite end extending downwardly 10 at 324 is adapted to contact cam segments 317, 318 on the disc 316. This lever 322 has three possible positions, one shown in Fig. 20 wherein said lever does not bear upon any of the cams mentioned in which case it is inoperative, a 15 second possibility (not shown) wherein it might bear against cams 317 and 318, and third, the position illustrated in Fig. 21 wherein arm 324 rides upon the concentric surface of disc 316 as shown. Cam 317 strikes follower 324 to move 20 cams 212 and 214 out for one course and as the said follower or lever 324 falls from cam 317 into the space between that cam and cam 318, will allow the cams 212 and 214 to move inwardly for a course after which they will be moved out as the follower is raised on cam 318 25 and thence to the surface of disc 316. This is conventional in Banner split foot machines of this type, being described in detail in British Patent 375,330 with respect to Figs. 3 and 5 of 30 the patent. Angular bracket 325 is attached to lugs 319, 320 and has pivoted at its lower end at 326 a lever 327 carrying an extension 328. This extension has an angular portion 329 for the purpose of contacting the round end 330 35 of pin 321 and pushing the same axially against the spring 331 shown compressed in Fig. 20. Pin 321 is threaded at the end 330 and has a nut 332 thereon which may be adjusted lengthwise of the pin and clamped in position by locking screw 333. A link 334 pivoted at 335 to lever 327, extends downwardly and is adjustably connected at 336 to a lever arm 337, having a cam engaging toe 338 which in turn contacts with certain cams upon cam drum 112.

40 Again referring to Figs. 9, 19 and 35, a post 339 has extending therethrough two spindles 340 and 341. An upright rod 342 is pivoted to a lever 343 which is fixed to spindle 340 and actuates the same in accordance with a cam on 45 cam drum 112' which bears upon one of the usual cam engaging levers which is attached to the lower end of said rod. Spindle 340 extends through post 339 and has fixed to its opposite end another arm or lever which connects to a link 344. This link is attached to the auxiliary cam block and serves to move the same either to or out of operative position. In a similar manner another rod 345 pivoted to lever 346 which is fast to spindle 341 rocks that spindle 50 and another lever at its opposite end to move another link 347 which controls the center cam only of said auxiliary cam block.

55 Referring to Figs. 6, 31, and 35 mechanism is shown for controlling the auxiliary yarn guide and also a cam which holds sinkers in advanced position at the auxiliary side during heel and toe knitting. A lever 348 is pivoted at 349 to an extension attached to the auxiliary cam block and this lever has an angular extension 350 at its upper end which is adapted to contact a cam element 351 attached to the outer end of auxiliary yarn guide 352 pivoted at 353 to latch ring 31. The lever 348 is actuated by means of a connecting link 354 engaging its lower end, said 60 link being pivoted to an extension 355 projecting

upwardly from a lever 356 which is pivoted to swing about a point 357 on a fixed portion of the cam plate 24. This lever 356 extends outwardly and downwardly and is actuated by means of a link 347 which same link was before mentioned as being connected to lever 346 for controlling the auxiliary center cam. A cam 358 has a stem 359 extending therefrom which slides radially in bracket 360. At the outer end of stem 359 I have adjustably secured by means of screws 361 bearing in an elongated slot 362, an offset hooked element 363, the hooked end 364 of which engages over the inner edge of the lever 348.

10 A slide 365 carrying at its inner end center cam 366 is adapted to slide radially within a slot formed in the sinker cap and is normally held in outer position for retracting sinkers, by means of a spring 367 which engages a pin 368 depending from said slide. Cam 366 engages within a 15 recess between the butts and nibs of the sinkers.

20 At certain times lever 348, Fig. 35, is swung in a clockwise direction whereby cam 366 will be pushed inwardly. When in this position, cam 366 does not retract sinkers as it would in normal operation while knitting, but allows the sinkers to continue around past the auxiliary feed while they remain in innermost position and hold the fabric down on the needles while the heel and toe are being knitted. When lever 348 25 is in a position corresponding to the innermost or inactive position of cam 366, auxiliary yarn lever 352 will be swung about its pivot to a non-feeding position. At all other times cam 366 30 will be withdrawn to the position shown in Figs. 35 31 and 35 in which time yarn lever 352 will be in feeding position, except during circular knitting on the main side.

35 During circular knitting and certain reciprocatory knitting in a split-foot machine it is a detrimental feature that some of the needles knitting at one side of the machine will have their butts contacted by the stitch cam at the opposite side of the machine so that stitches drawn at the first feed will tend to be drawn again or elongated 40 at the second feed. This tendency to produce uneven fabric has been overcome by a novel sinker and also by the use of the auxiliary needle raise cam 187. Referring to Figs. 27-29 the sinkers 369 are formed in the usual manner 45 except that the throat of the sinker has been cut out to form an added depression or recess 370 which functions to receive the loop which has been drawn and to allow the sinkers to be projected inwardly without extending that loop 50 in a manner to stretch or break the same. The needle 207 is shown in Fig. 27 about to measure its loop over sinker 369, and in Fig. 28, that needle is shown having drawn the loop down over the upper edge 371 of the sinker wherein 55 the loop has been fully measured. In Fig. 29 the sinker has been pushed inwardly to its maximum extent and while needle 207 is drawn down to the bottom of its stitch cam, the loop is not unduly stressed since it rests within the recess 60 370 provided for the purpose above mentioned.

65 The cam 187 is formed with a central raised portion 372 and with upwardly extending wing portion 373, 374. The needles in following through this auxiliary cam set will be drawn downwardly by one of the stitch cams 183, 184 but will be immediately raised to a higher level by means of one of the cam surfaces adjacent elements 372 and 373 or 374, and as a result of this, a stitch which has been drawn at the op- 70 75

posite yarn feed will not be held in a drawn position except at the lower point of one of the stitch cams. This in combination with the recessed throat of the sinkers assures that stitches which have been drawn at one feed will not be elongated by being held in an extended position for any length of time at the other feed. This provision is especially useful when the stitch length, due to fashioning, is greater on one side than on the other.

In Fig. 32 I have shown a modified type of auxiliary relief cam which corresponds in general to cam numbered 187. This cam indicated as 375 has a raised portion 376 extending between stitch drawing cams 183, 184 and also has upwardly projecting wing portions 377 and 378. This cam differs from the one shown in Fig. 26 in that horizontal surfaces indicated at 378' and 379 extend between the wing portions and the depressions immediately under the stitch cam. These two relief cams are to be used with the sinker cams shown in Figs. 33 and 34. The cam indicated at 380, Fig. 33, gives the sinkers a very rapid inward movement and it is necessary or at least desirable to use such a cam when the auxiliary cam 187 is to be employed. Sinker cam 381, Fig. 34 is adapted to give the sinkers a more moderate inward motion and cam 375 is preferably used with this type of sinker cam an easier motion being possible with this combination.

In the foregoing description I have described the mechanism which goes to make up the improved split-foot machine which is claimed herein and will now be described the operation of such machine in producing a typical split-foot stocking. While any of the modifications shown in Figs. 1-5 may be produced on this machine, the principles involved are the same in each case so that it will suffice to describe the operation relative to production of such a stocking as is shown in Fig. 1.

In Figs. 36-44 diagrammatic views showing the needle or jack cams and also the paths of needle butts and jack butts will assist in an understanding of the knitting cycle herein involved. In Fig. 1 I have shown a fashioned stocking having a welt portion 1 which has been knitted in a rotary manner, but it is to be understood that I may knit half hose wherein the usual rib top is transferred to the needles of the split-foot machine and wherein knitting of the ring top and leg continue on that machine as herein described. In case a ring top is to be knitted in continuation of the transferred rib welt the knitting is done at the main feed and the auxiliary cam block may be out of action at that time, but must be brought into action prior to knitting a leg portion 2, whether that leg portion is a continuation of the welt or whether it is in continuation of the ring top. The diagrammatic showing of Fig. 36 represents the cam positions and paths of the needle and jack butts during knitting of the leg. It is customary to bring the eyelet closing cam 213 into active position for one course just as the transition is made from knitting at the main feed to that at the auxiliary feed, thus raising a few (preferably three) jacks so that a few short butt needles will take the silk yarn, in case the leg is knit of silk, before the yarn which was being knitted at the main side has been withdrawn from the needles.

In Fig. 36 the path of the needle butts is represented by numeral 383. At this time instep cams 138, 139 and stitch cam 121 have been withdrawn

from operative position so that needle butts may pass the same without interference. The needle butts pass through the main cam block, stitch cam 121 being retracted, down under stitch drawing cam 122, over the rear needle raise cam 384 and up a cam indicated at 385 which raises said needle butts above stitch cam 183; these needle butts then contact center cam 185 and draw their stitches below stitch cam 184. Immediately thereafter these needles pass upwardly over relief cam 187 and on to front needle raise cam 386.

During the knitting of the leg the jacks are rotating idly and merely pass over stationary jack cams 211 and 215. A swinging cam indicated at 387, is in horizontal position at this time, being automatically raised to this position when cam 385 is projected inwardly against the cylinder.

Knitting of the leg is continued in a rotary manner until the top of high-splice 3 is reached. The high-splice herein shown is knitted by split-foot knitting and with the particular set up of jacks shown in Fig. 23. Said high-splice is formed on nine needles on each side less than the total complement of short butt needles, these nine needles on each side being in cooperation with long butt jacks 208. In Figs. 37 and 38 I have shown diagrammatically how the high-splice is knitted by reciprocation. Stitch cam 121 is brought in against the cylinder at the main yarn feed and high-splice and narrow sole cams 212 and 214 are brought into their intermediate position by means of lever 324 (Fig. 20, 21), cam segments 311, 318, etc.; cams 212, 214 are maintained in intermediate position wherein they engage long butt jacks only by means of elements 269, 271 bearing under screws 270, 272 all in a manner hereinbefore described. The nine short butt needles on each side which are above jacks 208, now function as though they were long butt needles since the jacks ride upon cams 212, 214 and thus raise these needles to the higher level during their reciprocations through the auxiliary cam block in either direction. Fig. 37 shows the long butt needles and short butt needles which have long butt jacks, passing through the auxiliary feed and drawing their stitches at stitch cam 183. The long butt needles pass up cam 387, cam 385 now being withdrawn, and do not knit at the main feed. The short butt needles with long butt jacks are raised up through pathway 388, as the long butt jacks ride up cam 214, to the same level the long butt needles were raised. The remaining short butt needles follow the lower pathway and do not knit at the auxiliary feed but do knit at the main feed drawing stitches by their butts passing under stitch cam 121. The short butt jacks follow a path similar to that indicated at Fig. 36 during these reciprocations. In Fig. 38 the reverse reciprocation is shown for knitting the high-splice and instep, long butt needles and short butt needles having long butt jacks knit at the auxiliary feed by their butts passing under cam 184 while the remaining short butt needles knit at the main feed as their butts pass under cam 122; instep cam 139 raises the long butt needles above the main cam block and cam 212 functions to raise the short butt needles with long butt jacks to the same level.

In Figs. 39 and 40 I have shown knitting during the heel, the arrows indicating the direction of knitting in each view. As shown in Fig. 1, heel 7 is produced on fewer needles than the

high splice and sole. This brings corner of the heel a few wales away from the suture line between high-splice and instep thus greatly strengthening the foot structure. During the 5 knitting of the heel, long butt needles, short butt needles having long butt jacks and also those having the three short butt jacks 209 are raised out of action, knitting continuing on the main side on only the short butt needles which are 10 left to form a small heel 7. Just before entering the heel, auxiliary center cam 185 is withdrawn from action and also cams 212, 214 are moved to inoperative position. Cam 210, known as the small heel or suture cam, is projected inwardly against the needle cylinder. Cam 139 15 raises all the long butt needles to inactive position and at the same time, cam 210 operates upon short butt jacks to raise them and their needles to the same inactive level to which the long butt 20 needles and short butt needles having long butt jacks are raised. Reciprocating knitting then continues throughout the heel, narrowing and widening in the usual manner. Cam 210 remains in position only long enough to raise all its jacks 25 and corresponding needles to inactive position before starting the heel. In the last reciprocation of the high-splice the long butt jacks were left in raised position.

After the heel is completed top instep cam 138 (Fig. 41) is brought inwardly against the cylinder to return all the inactive needles to a lower or active position. Cams 212, 214 are again brought to an intermediate position, that is, a position in which they engage long butt jacks 35 only, and knitting of the instep and sole continues in precisely the same manner in which knitting of the high-splice and instep was done. Fig. 41 shows knitting during this part of the foot. Instep cam 138 is only in its active position 40 long enough to lower all the inactive needles. A few courses before reaching the ring toe 8 a so-called bunion patch 9 is to be knit, this knitting being accomplished on an equal number of needles in both instep and sole. Cams 212, 214 are withdrawn at this time so that long butt jacks 208 45 no longer serve to make their corresponding needles function with the long butt needles so that split-foot knitting continues as is shown in Fig. 42 upon the long butt needles at the auxiliary side and an equal number of short butt needles knitting at the main side.

A ring toe 8 is knitted by all the needles knitting at the main feed (Fig. 43), drawing their 50 stitches but the butts of the needles passing under stitch cam 122 and passing through the auxiliary cam block but not knitting at that block. Cam 139 is withdrawn during this round and round knitting but cam 138 is brought into position to bring the long butt needles which were knitting 55 at the auxiliary side only, down to a level where they join the short butt needles and knit with the same. A toe may be knitted in the usual manner after knitting the ring toe.

After drawing stitches by cam 122 all the 60 needles pass around and are drawn down under cams 183, 184 and it is at such a time as this that auxiliary relief cam 187 comes into play for the purpose of immediately raising the needles to relieve the tension on the yarn which was 65 drawn at the main feed and tends to be drawn again at the auxiliary feed. The new type of sinker hereinbefore described also serves to relieve the strain on the fabric which is being held within the threads of the same at such a time. 70

75 The high-splice 3 has been shown reinforced

with an extra yarn 5 which additional yarn is inserted by means of the cam segments on disc 93 contacting a lever 91 and through its attendant mechanism in a manner hereinbefore described. This reinforcement may be made of any convenient width by adjustment of the segments 95-98 or by changing them for other segments of similar shape.

The cam operation just before starting the small heel is shown in Fig. 44. It is necessary to raise all the short butt needles which have jacks under them to the upper or inactive level and this is accomplished during the last course of knitting in the high-splice by means of cam 210. As shown in the last course mentioned (anti-clockwise in Fig. 44), cam 210 is in place, cams 212 and 214 are still in place and the short butt jacks as well as those having long butts will ride up cam 210 to raise their needles to practically the same level to which the long butt needles are raised by instep cam 139. When at this level and at the completion of that last course in the high-splice, knitting ceases on the auxiliary side and the heel is produced as shown in Figs. 39 and 40. Once the long butt needles 20 and short butt needles which have jacks are raised to their inactive level cams 210, 212 and 214 may be retracted.

The invention has been described relative to a specific machine for purposes of illustration 30 only and I do not intend to be limited by such specific disclosure except by the scope of the appending claims.

I claim:

1. In a split-foot knitting machine, a main 35 cam set, an auxiliary cam set, needles adapted to draw yarn and web holders cooperating therewith for knitting the yarn into a fabric, some of said needles and web holders knitting at one cam set and others at the other cam set, said web holders having means therein for relieving the tension on loops held thereby which loops have been drawn at one cam set and tend to be redrawn at the other cam set.

2. In a split-foot knitting machine having a 45 main cam set and an auxiliary cam set, needles for drawing yarn and sinkers cooperating therewith, some of said needles and sinkers drawing yarn and knitting at one cam set and others drawing yarn and knitting at the other cam set, 50 and means acting upon needles between and at either side of the stitch cams at one cam set for relieving the tension on stitches which have been drawn at one cam set as those same stitches tend to be redrawn at the other cam set.

3. A split-foot knitting machine wherein needles and cooperating sinkers knit yarn at a main 55 cam set and at an auxiliary cam set, some of said needles and sinkers which have drawn yarn at one of the cam sets operating in such a manner that they tend to redraw their stitches upon passing through the other cam set, means for preventing elongation of these loops which tend to be redrawn including recesses in sinker throats whereby loops may be held in said recesses for 60 the purpose described.

4. In a split-foot knitting machine, a main 65 cam set and an auxiliary cam set, needles for drawing yarn and sinkers cooperating therewith to form said yarn into knitted loops, some of 70 said needles and sinkers drawing loops at one cam set while others draw yarn at the other cam set, the operation being such that loops drawn at one of the cam sets tend to be redrawn at the other, said sinkers having throats therein and 75

recesses at the rearmost portion of the throat within which the loops will be held as they pass through the second cam set tending to be redrawn thereat.

5. A split-foot knitting machine having in combination a main cam set and an auxiliary cam set, needles for drawing yarn and sinkers cooperating therewith for knitting said yarn into loops, some of the needles and sinkers knitting at one cam set and others knitting at the other cam set, stitch cams at both cam sets, an auxiliary needle raise cam at one of the cam sets adapted to maintain needles passing through that cam set in an elevated position except at 10 the lowermost portions of the stitch cams, and said sinkers being constructed with tension relieving means therein whereby elongation of the loops held on needles and sinkers will be prevented as they tend to be redrawn at one of the 15 cam sets.

6. Mechanism as defined in claim 5 wherein said auxiliary raise cam is formed in a manner to guide needles above the lowest point at which they would be drawn by the stitch cams except 20 immediately adjacent the lowermost point of the stitch cams.

7. In a split-foot knitting machine needles and sinkers adapted to knit fabric, said needles being divided into opposite groups having long 30 and short butts, a bracket attached to said machine having slidably mounted therein upper and lower instep cams, said lower instep cam being actuated from a linkage connected to one moving element of the machine and said upper instep cam being actuated by linkage connected to an 35 entirely separate part of the machine for individual actuation thereof.

8. In a split-foot knitting machine having a main yarn feed at which the top, high-splice, 40 heel, sole, ring toe and toe of a stocking are adapted to knit and an auxiliary feed at which the leg and instep are knitted, a needle cylinder, needles and sinkers for drawing stitches at said feeds, jacks cooperating with some of the 45 needles at certain times, said jacks having butts of at least two lengths, cams for controlling said jacks, means for projecting said cams inwardly against the needle cylinder where they engage all 50 the butts and means for limiting the movement of said cams inwardly whereby they do not engage the shorter butts.

9. A split-foot knitting machine having therein needles divided into opposite groups of long and short butts, jacks cooperating with certain 55 short butt needles, said jacks being divided into groups having long and short butts, cams for operating said jacks, means for withdrawing said cams to a position in which they will not contact the butts of the jacks said means being operable to allow said cams to slide inwardly to a 60 position in which they contact all the butts of said jacks in combination with means for limiting the inward movement of said cams to such a position that they will contact long jack butts 65 but will not contact the short jack butts.

10. The mechanism of claim 9 wherein said last mentioned means comprises a sliding element having cams adapted to project between a fixed portion of the frame of said machine 70 and limiting elements attached to said cams whereby the cams will be maintained in a position to contact long butts but not short butts of said jacks.

11. In a split-foot knitting machine needles 75 and sinkers adapted to knit fabric at two sepa-

rate yarn feeds, said needles being divided into opposite groups of long and short butts, jacks divided into groups having long and short butts which cooperate with the short butt needles adjacent the terminal long butt needles, cams for 5 engaging the butts of said jacks, operating mechanism for withdrawing said cams to a position in which they do not contact any of the butts on said jacks, resilient means attached to extensions on said cam and to fixed elements on said machine for forcing said cams inwardly when said operating mechanism permits and a sliding bar bearing cam-like elements adapted to be projected between fixed portions of said machine and limiting elements on said cam extension at 10 certain predetermined intervals whereby said cams when allowed to slide inwardly under the influence of said resilient means, will be maintained in a position to engage long butt jacks but 15 not short butt jacks.

12. A knitting machine having needles, sinkers and two feeding stations and cams at each feeding station for effecting the knitting of split-work fabric, there being relative reciprocatory movements between the cams and needles, the 20 cam means at one feeding station being shaped to elevate the needles thereby to relieve strain on stitches that were last knitted at the other feeding station when said needles and cam means are in such relative positions that the said cam 25 means act upon the needles, and sinkers so constructed and operated as to cooperate with the cam means in relieving the strain.

13. A knitting machine adapted to knit split-work fabric and having two feeding stations at 30 each of which one of two yarns is knitted by one of two sets of needles, and the construction being such that needles which knit at one station pass through the cams at the other station and tend to redraw their stitches as they pass beneath 35 cams thereat, means for joining the fabric sections during knitting, means including an auxiliary or center raise cam acting in conjunction with one feeding station to elevate needles and thereby avoid unnecessary extension of loops 40 formed by said needles at the other feeding station.

14. In a split-foot knitting machine having a main cam set and an auxiliary cam set, needles for drawing yarn and sinkers cooperating therewith, some of said needles and sinkers drawing 45 yarn and knitting at one cam set and others drawing yarn and knitting at the other cam set, and means including cooperating needles and notched sinkers for relieving the tension on 50 stitches which have been drawn at one cam set as those same stitches tend to be redrawn at the other cam set.

15. A knitting machine having needles, two feeding stations and cams at each feeding station for effecting the knitting of split-work fabric, there being relative reciprocatory movements between the cams and the needles, and the construction being such that needles which knit at one station pass through the cams at the other 60 station and tend to redraw their stitches as they pass beneath cams thereat, the cam means at a feeding station at which stitches tend to be redrawn being shaped to elevate needles thereby to relieve strain on stitches knitted at the other 65 feeding station.

16. In a split-foot knitting machine, a cam set and an auxiliary cam set, needles and web holders functioning, some at one cam set and others at the other cam set, to draw and knit yarns, stitch 70

5 cams at both cam sets, the construction being such that needles drawing stitches of one of the 10 yarns at one cam set pass beneath stitch cams of the other cam set thereby tending to elongate or redraw those stitches, an auxiliary raise cam at said other cam set adapting to raise needles which knitted at the first cam set immediately after those needles pass beneath a stitch cam whereby elongation of stitches drawn at the first cam set will be minimized.

10 17. A needle cam set including stitch cams and an auxiliary raise cam positioned below the stitch cams of said needle cam set and extending between and to either side thereof, the needle butt 15 engaging surface of said raise cam being depressed substantially the width of a needle butt below the lower points of said stitch cams and extending upwardly to a horizontal surface between them, said surface serving to elevate the needle butts to a level above that to which they are 20 drawn by a stitch cam, the raise cam then extended upwardly and outwardly to form wing portions at the outer edges of said stitch cam.

18. For use in a circular, independent needle, two-feed split-foot knitting machine in which 25 stitches are drawn at one side of the machine and tend to be redrawn at the other, a sinker having a throat defined by a substantially horizontal edge over which stitches are to be measured and drawn and a nib, and a recess or notch at the 30 back of said throat extending below said edge within which stitches may be held to avoid strain upon being redrawn, when sinkers are projected inwardly to perform their web holding function.

35 19. For use in a circular, independent needle, two-feed split-foot knitting machine wherein 30 stitches drawn at one side of the machine tend to be redrawn at the other, a sinker having a throat defined by a yarn drawing edge and a nib, 40 said yarn drawing edge being notched for the reception of loops which have been drawn so that when they tend to be redrawn they will not be elongated.

20. For use in a circular, independent needle,

two-feed split-foot knitting machine wherein 5 stitches are drawn at one side of the machine and tend to be redrawn at the other, a sinker having in combination a nib, a throat below said nib, a substantially horizontal edge over which 10 stitches are to be drawn and a notch in said edge and at the back of said throat within which 15 stitches are to be held as they tend to be redrawn so that they will not be strained or elongated.

21. A sinker for use in a circular, independent 20 needle, two-feed split-foot knitting machine, said sinker having a throat defined by a yarn drawing edge and a nib, the said throat being recessed to avoid straining of the loops or stitches.

22. A sinker for use in a circular, independent 25 needle, two-feed split-foot knitting machine comprising a nib and throat, said throat extending substantially horizontally and having a downwardly extending recess at the rearmost portion thereof.

23. A sinker for use in a circular, independent 30 needle, two-feed split-foot knitting machine having nib and throat portions, said throat having a substantially horizontal lower surface over which loops are adapted to be measured, and a 35 downwardly and rearwardly extending recess at the rearmost portion thereof.

24. A sinker for use in a circular, independent 40 needle, two-feed split-foot knitting machine, said sinker having a throat defined by a yarn drawing edge and a nib, the yarn drawing edge having a notch or recess therein within which loops may be held to avoid strain thereon as said loops are redrawn.

25. A sinker for use in a circular, independent 45 needle, two-feed split-foot knitting machine having a throat defined by a substantially horizontal edge over which stitches are to be measured and drawn and a nib, and a recess or notch at the 50 back of said throat extending below said edge within which stitches may be held to avoid strain upon being redrawn when sinkers are projected inwardly to perform their web holding function.

ROBERT H. LAWSON.
